HENRY E. MUCHNIC, OF ATCHISON, KANSAS.

RAIL JOINT.

Application filed November 14, 1927. Serial No. 232,970.

My invention relates to means whereby continuous wheel engaging portions are provided to compensate for the contraction and expansion of railroad tracks due to variations in 5 temperatures.

My invention also involves the provision of compensating means whereby the contraction gaps will be divided; that is to say, my invention contemplates means of such character 10 that the undesirable large gap, resulting from the accumulation of contraction at one point, is eliminated.

My invention also has for its object the provision of a construction wherein contraction 15 and expansion of the rails is readily permitted and proper support for the bottoms of the rails as well as for the bottom of the rail-heads is also provided; while means are provided for carrying the car-wheels over the 20 gap.

The above enumerated objects, as well as others, and the advantages of my invention, will all be readily comprehended from the detailed description of the drawings, 25 wherein—

Figure 1 is a side elevation of the adjacent ends of two rails provided with one form of my improved expansion joint.

Figure 2 is a top plan view of same, with a 30 portion broken away and shown in section.

Figure 3 is a cross-sectional view taken on the line 3—3 of Figure 1 looking in the direction of the arrows.

Figure 4 is a perspective view of an end of 35 a rail shown adapted to receive my improved expansion joint.

Figure 5 is a top plan view illustrating a modification.

Figure 6 is a top plan view, with a portion 40 broken away and in section, showing a further modified form of my invention.

Figure 7 is a cross sectional view taken on the line 7—7 of Figure 6 looking in the direction of the arrows.

Figure 8 is a perspective view in section, 45 showing another modification of my invention.

Figure 9 is a similar view of a further modification; the rail ends being omitted.

Figure 10 is a similar view of another modification of the invention.

In the exemplification of the invention as disclosed in the first four figures of the drawings, 15, 15 illustrate the ends of two aligned 55 rails; the ball or head portions whereof are

cut away on the inner or gauge side to a pre-determined extent lengthwise as shown at 16 in Figure 4, in order to receive the easer rail top portion 17 of my improved expansion joint.

The joint, in this construction, comprises the gauge side or rider section 18 which is preferably provided with a rail-head reinforcing flange or rib 19 and with a rail-web engaging lower rib 20. The rider section 18 is provided with a base 21 which is slotted at 22 to receive the base flanges of the adjacent rails 15, 15, thus permitting the base of section 18 to extend beneath the rails and take the place of a tie-plate.

The opposite or outer side of the joint comprises an easer section 23, having a cut-away head portion 24 provided with a flange or rib 25 adapted to fit beneath the heads of the two rails; the head portion 24 extending preferably slightly above the tops of the rails as shown in Figure 3 to ease the wheels over the joint. The section 23, like section 18, has a flange or rib 26 adapted to engage the rail webs at a point opposite to the rib 20 of the 70 rider section 18; and the base of the easer section 23 is also slotted lengthwise, like section 18, to receive the base flanges of the two aligned rails; with the base of section 23 also extending beneath the base of the rails. The 75 base portions of both sections 18 and 23 are made to leave a slight space therebetween as shown at 27 in Figure 3; while the sides of the two sections are apertured to receive the bolts 28 which extend through openings in the webs 80 of the two rails 15, 15. The openings in the rails are preferably in the nature of slots as shown at 29 in Figures 1 and 2 to allow longitudinal movement for expansion of the rails; the bolts being preferably provided with 85 spacer thimbles 30, and the sections 18 and 23 with ribs 19, 20 and 25, 26, in order to prevent a too firm gripping relation between the joint members and the rails, and permit expansion.

The two sections 18 and 23 are of equal 90 length and the head portion 24 of the easer section 23 extends the full length of said section and therefore beyond the cut-away portions 16 of the rail-heads, as shown in Figure 2; while the head portion 17 of the rider section 18 is arranged intermediate of the ends 95 of section 18 and substantially equal to the combined lengths of the cut-away portions 16 of the two rails, as shown in Figures 1 and 2.

The two sections 18 and 23 are of equal 100 length and the head portion 24 of the easer section 23 extends the full length of said section and therefore beyond the cut-away portions 16 of the rail-heads, as shown in Figure 2; while the head portion 17 of the rider section 18 is arranged intermediate of the ends 105 of section 18 and substantially equal to the combined lengths of the cut-away portions 16 of the two rails, as shown in Figures 1 and 2.

In Figure 5 I show a modification of the invention consisting of two interchangeable sections 31, 32. These sections are substantially similar; each having a base portion similar to that of sections 18 and 23, with rail-web engaging ribs like ribs 19, 20, 25, 26 and slotted to receive the base flanges of the rails.

The sections 31 and 32 are each provided with a head or rider portion 33, preferably of less length than the base portions of said sections and preferably a shorter distance from one end than from the other end of the section; the web portions being apertured to receive the bolts 28, which extend through openings—preferably slots—in the webs of the rails.

When this construction is employed, the heads of both rails 15, 15 are cut away on opposite sides to an extent slightly longer than the lengths of the rider or head portions 33 of the expansion joint members; the cut-away on one side of the rail being to a greater extent as shown at 34 than the cut-away on the opposite side as shown at 35, in order to accommodate the offset or staggered positioning of the head portions 33 of the two sections 31, 32.

It is apparent that with this construction both sections 31 and 32 may be similar and a single pattern may be employed in the making of the sections; each section 31 and 32 being capable of use either on the inside or gauge side of the rails or on the outer sides as easer rail sections.

In Figures 6 and 7 I illustrate another form of my invention wherein the joint for the ends of the rails 15, 15 comprises a dummy rail section 36 which is adapted to be aligned with the ends of the two rails 15, 15 and is of similar rail configuration. The dummy rail section 36 is secured in place and held in alignment with the main rails 15, 15 by the inside or gauge section 37, of greater length than the dummy rail, which is provided with an inwardly disposed flange or shoulder 38 at the top to engage beneath the head of the dummy rail section 36 as well as beneath the heads of the rails 15, 15. The gauge section 37, adjacent the bottom, is also provided with an inwardly disposed flange or rib 39 adapted to engage the bottom of the web portion of the dummy rail section 36 and the web portions of the rails 15, 15. The section 37 is provided with a base 40 slotted lengthwise on the inner side to receive the base flange 41 of the dummy rail section 36 and the base flanges of the rails 15, 15.

The opposite or outer side of the dummy rail section 36 is provided with an easer rail section 42 of greater length than the dummy rail section and which may be substantially similar to easer rail section 23 previously described, being provided with the inwardly disposed rib or flange 43 adjacent the top to extend beneath the heads of the dummy rail

section 36 and of the rails 15, 15 and also provided with a rib or flange 44 adjacent the base to engage the bottom of the webs of the rails and of the dummy rail section 36 at a point opposite to the engagement thereby of the rib or flange 39. The easer rail section 42 is also shown provided with a base 45, the inner side whereof is grooved or slotted lengthwise at 46 to receive the flange of the base of the dummy rail section 36 as well as the flanges of rails 15, 15. The sections 37 and 42, as well as the dummy rail section 36, are apertured at registering points to receive the bolt 47 whereby the three members are firmly clamped together when the nut 48 is firmly screwed onto the bolt 47. The gauge section 37 and rider section 42 are of length greater than the length of the dummy section 36 so as to lap the ends of the main rails 15, 15, as shown in Figure 6, to which the sections 37 and 42 are secured by means of the bolts 49 which latter are preferably provided with the thimbles 30 in order to prevent a too firm clamping relation between the expansion joint sections 37, 42 and the main rails; the webs of the latter being also preferably provided with the slots 29 in order to permit longitudinal expansion of the main rails.

In Figure 8 I illustrate a modification of the rail joints shown in Figures 6 and 7 in that instead of employing a three piece expansion joint as in Figures 6 and 7, the dummy rail section 50, gauge section portion 51 and easer rail section 52 are all cast integral, thus providing a single piece expansion joint wherein the dummy rail portion or section 50, like the dummy rail section 36 in Figure 7, is of length less than the lengths of the sections 51 and 52 in order that the spacing at the ends intermediate of the sections 51 and 52 may receive the webs of the ends of the two aligned rails 15, 15. The joint element is bolted slidably to the rails 15, 15, as previously described, preferably by providing the webs of the main rails with slots as at 29.

It is apparent that with the constructions shown in Figures 6, 7 and 8, previous preparation or longitudinal cutting away of the main rails is made unnecessary. It will be understood that the ends of the expansion joint construction shown in Figure 8, beyond the dummy rail section portion 50, will have the transversely disposed slot in the base portion, of configuration similar to that outlined at 53 in Figure 8, in order to receive the base flanges of the main rails 15, 15, with the web portions of the rails disposed between the rail sections 51 and 52. A single base expansion joint is thus provided extending about both sides and the bottom of the main rails 15, 15.

In Figure 9 I illustrate a further modification of the invention, wherein the rail joint forming element consists of the inner or gauge side section 54 formed at the top to extend beneath the head of the main rails; said

section being provided with the inwardly disposed ribs 55 adapted to engage the webs of the main rails and having an outwardly disposed flange portion 56 at the bottom which 5 is adapted to lap the flange of the main rail to abut against a rib 57 formed on the base portion 58 of the easer section 59. The easer rail section is provided with a head portion 60 adapted to extend along the side of the 10 head of the main rails, as shown in Figure 2; the easer rail section being also provided with the inwardly disposed rib or flange 61 adapted to engage the webs of the main rails. The easer rail section 59 is provided with a base 15 of greater width than the base portions of the structures shown in Figures 3 and 7 in order to extend to opposite sides of the main rails; the easer rail side of the base being undercut or slotted at 62 to receive the flange 20 of the main rails, while the opposite or inner side of the base portion 58 is shouldered at 63 to provide abutment for the inner side of the base flange of the main rails. It will be understood, of course, that the portions 25 54 and 59, as in the previously described constructions, are apertured to receive suitable bolts whereby the main rail sections are slidably clamped therebetween. The expansion joint just described and shown in Figure 9 30 consists of a two-piece construction and one which will require no special preparation or cutting away of the main rails.

In Figure 10 I show a modified form of the construction shown in Figure 9 in so far that 35 the inside or gauge section 64 and the outside or easer section 65 are made independent of the main base portion 66. In other words, a three piece construction of expansion joint is shown in Figure 10. The inside or gauge 40 section 64 in Figure 10 is substantially identical with section 54 shown in Figure 9 and the outside or easer section 65 is substantially similar to section 59 except that the bottom is not formed integral with the main piece 45 66, but has its bottom flange 67 extend into the longitudinal groove or slot 68 formed in the shouldered portion 69 of the base portion 66 as is the case with the bottom flange 70 of the inside or gauge section 64 which ex- 50 tends into the longitudinal groove or slot 68 of the opposite shoulder portion 69 of the main base 66. With this construction the ends of the main rails 15, 15 need not have their heads longitudinally cut away as in the con- 55 struction shown in Figures 3 and 5, as the full formed balls or heads of the main rails will rest on top of the gauge section 64 and on the inwardly disposed flange portion 71 of the easer rail section 65; it being under- 60 stood, of course, that the two sections 64 and 65, as in the previously described constructions, are apertured at points adapted to align with apertures in the webs of the main rails for the purpose of receiving suitable 65 bolts whereby the respective elements are se-

cured to the main rails, at the same time allowing the rails to move longitudinally in the joints.

As the base portions of all of the forms of rail joints shown in the drawings are of considerable length, they will extend across a number of ties and will permit spiking of the base portions of the joints to the ties; these base portions in all instances eliminating the use of the usual tie-plates at these particular 70 points in the track.

It is also apparent that with all of the constructions, a slip joint is provided with outside means for carrying the wheels over the gaps at the joint; and that in all of the constructions, except those shown in Figures 9 and 10, a plurality of gaps are provided, namely at both ends of the head portion 17 of the rider section 18 shown in Figures 2 and 3; at both ends of the head portion 33 of the sections 31 and 32 in Figure 5; and at both ends of the dummy section 36 or 50 of the constructions shown in Figures 7 and 8. That is to say, with my improved expansion joint the usual expansion gap at present encountered in railroad track construction is reduced to substantially half its size, because the gap is split in half as it were and smaller gaps thus provided with the result 80 that an easier riding rail is obtained.

It is also apparent from the constructions that have been shown and described, that my improved expansion joint provides support for the bottom of the rail heads and bottoms of the rails and that in all instances the base 100 portions of my joint-forming members take the place of the usual tie plate; while the main rails, in all instances, may be said to be enclosed by the joint-forming elements, with the result that a more secure joint is provided. 105 At the same time the relation between the joint-forming elements and the main rails is such that binding between the joint forming members and rails is impossible and hence free longitudinal movement of the rails permitted; and at the same time means are provided in all forms of my rail joint for carrying the wheels over the gap.

The drawings disclose various embodiments of my invention which have been described in terms employed merely as terms of description and not as terms of limitation, as structural modifications may be made without, however, departing from the spirit of my invention.

What I claim is:

1. In combination with a pair of rails each having a portion of its head cut away, a rail joint consisting of a rider section and an easer section, said easer section being provided with a head portion intermediate of its ends adapted to match the cut-away section of the heads of both rails, each section having a base portion adapted to extend transversely of the upper and lower faces of 120 125 130

the bases of the aligned rails, spacer means intermediate of both sections and disposed through the webs of the aligned rails, and means whereby the sections and rails are secured together and longitudinal movement of the rails permitted.

2. In combination with a pair of aligned rails, a rail joint composed of an inside section, an outside section and a base section, the base section being formed to support the rails and the first mentioned sections and pre-

vent lateral movement of the latter, the first mentioned sections having vertically spaced rail-web engaging projections, spacer means disposed through the webs of the rails intermediate of the first mentioned sections, and means for securing said first mentioned sections to the rails while permitting longitudinal movement of the rails relative to all of said sections.

15
